ROLLER BIT

Alfred C. Catland, Alhambra, Calif., assignor to
 Globe Oil Tools Company, Los Nietos, Calif.,
 a corporation of California

Application January 14, 1936, Serial No. 59,075

15 Claims. (Cl. 255—71)

This invention relates to a well drilling tool and relates more particularly to a roller bit for use in the rotary method of well drilling. A general object of this invention is to provide a practical effective and long wearing roller rock bit.

Another object of this invention is to provide a roller bit in which the several roller cutters are carried by a small, compact and strong removable carrier.

10 Another object of this invention is to provide a roller bit in which the screws attaching the cutter carrier to the bit body are not subjected to any stresses resulting from the drilling operation so that these screws and the body parts in 15 which they thread may be small, to promote the drilling efficiency of the bit.

Another object of this invention is to provide a roller bit of the character mentioned in which the screws securing the cutter carrier to the bit body have their heads in the carrier assembly and thread outwardly into openings in the legs of the body whereby said legs may be relatively light or small to promote the general efficiency of the bit.

Another object of this invention is to provide 25 a roller bit embodying improved bearing bushings on the carrier for rotatably supporting the cutters, which bushings may be treated or hardened to be long wearing and operate to protect the carrier against the action of the rotating cutters 30 so that the carrier may be formed of tough, strong material.

Another object of this invention is to provide a roller bit of the character mentioned in which the bushings rotatably supporting the cutters directly transmit to the body of the bit the stresses, resulting from the active contact of the cutters with the formation, thereby relieving the carrier and the carrier securing screws of these stresses.

Another object of this invention is to provide a 40 roller bit of the character mentioned in which the bearing bushings have integral thrust washers or flanges receiving the end thrusts from the cutters.

A further object of this invention is to provide a roller bit that is efficient in operation and that 45 embodies a minimum number of simple, sturdy parts.

The various objects and features of my invention will be fully understood from the following detailed description of a typical preferred form 50 and application of my invention, throughout which description reference is made to the accompanying drawings, in which:

Fig. 1 is a side elevation of the bit provided by this invention with a portion broken away to illustrate the rotatable mounting of one of the

outer cutters. Fig. 2 is an enlarged longitudinal detailed sectional view of the bit body and the assembly of the carrier and cutters. Fig. 3 is a bottom elevation of the bit. Fig. 4 is a bottom elevation of the bit body with the cutter carrier 5 removed. Fig. 5 is a fragmentary vertical detailed sectional view similar to Fig. 2 illustrating the manner of assembling the carrier in the body. Fig. 6 is a side elevation of a bushing for carrying one set of inner cutters. Fig. 7 is an end view 10 of the bushing illustrated in Fig. 6. Fig. 8 is a side elevation of a bushing for carrying an outer cutter. Fig. 9 is an end elevation of the bushing illustrated in Fig. 8. Fig. 10 is a top or plan view of the cutter carrier. Fig. 11 is a side elevation 15 of the cutter carrier and Fig. 12 is a transverse detailed sectional view taken as indicated by line 12—12 on Fig. 2.

The well bit provided by this invention includes, generally, a shank 10, a bit head or body 11 removably attached to the shank 10, a spider or carrier 12 detachably secured to the body 11, outer roller cutters 13 and sets of inner cutters 52 and 53 supported by the carrier 12.

The shank 10 is adapted to be connected with 25 the lower end of a well drilling string and is provided to carry the bit body 11. In practice the shank 10 may be a simple elongate member provided at its upper end with means for facilitating its connection with the drilling string. In the 30 particular case illustrated in the drawings the upper end of the shank 10 is provided with a tapered screw threaded pin 15. The lower end portion 16 of the shank 10 is shaped and proportioned to carry the body 11 being cylindrical in 35 shape and being reduced in diameter. An annular downwardly facing shoulder 17 occurs at the upper end of the reduced shank portion 16. A central longitudinal fluid passage 18 extends through the shank 10 from one end to the other. 40 A fluid discharge device or nozzle 19 is provided at the lower end of the passage 18. The nozzle 19 may fit a tapered socket 20 at the lower end of the passage 18. A plurality of downwardly and outwardly inclined discharge ports 21 is provided 45 in the nozzle 19.

The bit head or body 11 is detachably secured to the shank 10 to extend from its lower end and the projecting portion of the body 11 is shaped and formed to receive the carrier 12 and its cutters. In accordance with the broader aspects 50 of the invention the body 11 may be removably secured to the shank 10 in any suitable manner. In the form of the invention illustrated in the drawings the bit body 11 is connected with the 55

shank 10 by an effective bayonet type joint. The body 11 is socketed or tubular having a central longitudinal opening 22 receiving the reduced end portion 16 of the shank 10. Diametrically opposite bayonet slots or grooves are provided in the wall of the body 11 to receive lugs 23 on the shank portion 16. Each of these bayonet grooves includes a substantially vertical portion 24 extending downwardly from the upper end of the body 11 and a substantially horizontal portion 25 joining the lower end of its vertical portion 24. The shank portion 16 may have flat vertical surfaces 26 to form the inner walls of the vertical groove portions 24. The bit body 11 may be arranged on the shank portion 16 so that the lugs 23 are received in the vertical portions 24 of the bayonet grooves. Upon the inner ends of the vertical groove portions 24 receiving the lugs 23 the body 11 may be turned relative to the shank 10 so that the lugs 23 are received in the inner ends of the transverse groove portions 25. Keys 27 are then inserted in the vertical portions 24 of the bayonet grooves to lock the lugs 23 in place. The parts are preferably related so that the keys 27 are entered behind the lugs 23 relative to the direction of rotation of the bit. Screws 28 may be threaded in openings in the shank 10 at the upper ends of the keys 27 to prevent the upward displacement of the keys. With the bit body 11 secured to the shank 10 by the bayonet slot connection just described the upper end of the body may bear upwardly on the shank shoulder 17.

The lower projecting portion of the body 11 which is provided to receive the carrier 12 is provided with two sets of diametrically opposite legs 29 and 30. The legs 29 and 30 are spaced approximately 90° apart and project downwardly and somewhat outwardly as illustrated in Figs. 1, 2 and 5 of the drawings. The opposite sides 40 of the legs 29 and 30 may converge downwardly so that the legs are of relatively small dimensions at their lower ends. The legs 29 have inner surfaces 31 inclined downwardly and outwardly relative to the longitudinal axes of the bit. Downwardly facing shoulders 32 are provided on the surfaces 31 adjacent their upper ends. Substantially vertical inner surfaces 33 are provided on the legs 30. Each surface 33 is provided with a downwardly facing shoulder 34 spaced a considerable distance above its lower end.

The carrier 12 is a spider-like part assembled within the series of legs 29 and 30 to carry the cutters 13 and the cutters 52 and 53. The carrier 12 is preferably integral and includes a main bridge or web 35. The web 35 is disposed transversely or horizontally and has its principal axis in the plane of the vertical axes of the diametrically opposite legs 29. The web 35 is substantially wedge shaped in vertical cross section having downwardly or inwardly inclined sides. Downwardly and outwardly inclined annular thrust surfaces or bearing surfaces 36 are provided at the opposite ends of the web 35. The surfaces 36 are spaced from and substantially parallel to the inner surfaces 31 of the legs 29. In accordance with the invention tapered screw threaded pins 37 project upwardly and outwardly from the bearing surfaces 36. The longitudinal axes of the pins 37 are substantially normal to the surfaces 31 and 36. Central openings or sockets 38 enter the pins 37 from their outer ends. The parts are proportioned so that the outer ends of the pins 37 are spaced some distance from the inner sides 31 of the legs 29. The cutter carrier 12 includes integral pins 39 projecting from

the opposite sides of its web 35 toward the legs 30. The pins 39 are threaded and suitably tapered. In the preferred construction the pins 39 are inclined downwardly and outwardly having their longitudinal axes lying in the vertical plane of the legs 30. As the carrier 12 merely forms a mounting for the cutters 13 and 14 and does not directly rotatably support the cutters it may be formed of a tough steel to be capable of dependably withstanding the stresses and forces to which it may be subjected.

The outer cutters 13 are provided to act on the outer portion of the well bore and are positioned between the inner sides of the legs 29 and the surfaces 36 of the carrier 12. The outer cutters 13 are substantially frusto-conical roller cutters having suitable peripheral cutting teeth 40. The outer ends of the cutting teeth 40 are bevelled away as at 41. Each outer cutter 13 has a central longitudinal opening 42.

The invention provides novel and particularly effective bearing bushings 43 for rotatably supporting the outer cutters 13. The bushings 43 are threaded on the pins 37 having sockets 44 receiving the threaded pins. The bushings 43 are carburized or otherwise hardened to be very long wearing. The inner ends of the wear taking bushings 43 may bear on raised portions of the surfaces 36. Each bushing 43 is provided with a cylindrical external bearing surface which rotatably carries an outer cutter 13. It may be preferred to rotatably support the cutters 13 on the bushings 43 through suitable roller bearings 45. The inner ends of the cutters 13 may have thrust transmitting cooperation with the annular surfaces 36 of the carrier 12. In accordance with the invention the bushings 43 are provided at their outer ends with integral thrust washers or thrust flanges 46 to receive the principal end thrusts from the cutters 13. The outer sides of the flanges 46 which also form the outer ends of the bushings 43 bear outwardly against the inclined inner surfaces 31 of the legs 29 for the direct transmission of the drilling forces and stresses between the body legs and the cutter supporting bushings. An upwardly facing shoulder 47 is provided on the outer side of each flange 46 to cooperate with the shoulder 32 on the inner side of a leg 29. The cooperation of the shoulders 47 and 32 locks the bushings 43 against unthreading from the pins 37 and provides for the effective transmission of the drilling pressures and forces between the cutter supporting bushings 43 and the bit body 11. The flanges 46 of the bushings 43 may extend downwardly beyond the lower ends of the body legs 29 and their lower ends may be suitably bevelled.

Bolts or screws 48 connect the pins 37 of the carrier 12 with the body legs 29. Openings 49 are provided in the flanges 46 or the outer end parts of the bushings 43 and aligned threaded openings 50 are provided in the legs 29. The screws 48 are positioned to have their heads 51 in the sockets 38 and to extend outwardly through the openings 49 and thread into the openings 50. Wrench sockets 63 are provided in the outer ends of the screws 48. The heads 51 of the screws 48 are adapted to bear outwardly against the bushings 43 at the outer ends of the pins 37. The screws 48 serve to connect the carrier pins 37 with the legs 29 but are not subjected to the drilling forces and stresses as these forces and stresses are directly transmitted by the cooperating surfaces of the bushings 43 and the legs 29. The outer cutters 13 rotatably supported on the bushings 75

43 as just described project downwardly beyond the lower ends of the legs 29 and rotate about downwardly and inwardly inclined axes.

The inner cutters 52 and 53 are provided to act on the major inner portion of the well bore and are provided in series or sets positioned between the body legs 30 and the web 35 of the carrier 12. Each set of inner cutters comprises two roller cutters 52 which may be of the same diameter and a larger roller cutter 53 forming the outermost cutter of the set. The cutters 52 and 53 are preferably cylindrical and are provided with suitable cutting teeth. The bit includes simple, effective bearing bushings 54 for rotatably supporting the sets of inner cutters. The bushings 54 have central longitudinal openings 55 whose inner portions are threaded to receive the pins 39 of the carrier 12. An inwardly facing shoulder 56 is provided on the wall of each bushing opening 55. When the bushings 54 are properly threaded on the carrier pins 39 the inner ends of the bushings may bear on the downwardly convergent sides of the carrier web 35. The bushings 54 have cylindrical external bearing surfaces for rotatably carrying the cutters 52 and 53. The cutters 52 and 53 may be rotatably supported on the bushings 54 through suitable roller bearings 57. The inner ends of the innermost cutters 52 may bear on the sides of the carrier web 35.

30 The invention provides integral thrust washers or flanges 58 on the bushings 54 to receive the principal operating thrusts from the inner cutters. The inner surfaces of the flanges 58 are normal to the longitudinal axes of the bushings 54 while the outer surfaces of the flanges 58 bear on the inner surfaces 33 of the legs 30. Upwardly facing shoulders 59 are provided on the outer sides of the flanges 58 to cooperate with the shoulders 34 on the legs 30. The cooperation of the shoulders 59 with the shoulders 34 locks the bushings 54 against unthreading from the pins 39 and dependably transmits the drilling forces directly between the body 11 and the bushings 54. The lower ends of the flanges 58 which may extend beyond the lower ends of the legs 30 may be suitably tapered or bevelled.

45 Screws 60 are provided to connect the pins 39 and their bushings 54 with the adjacent body legs 30. The screws 60 are passed outwardly through the openings 55 in the bushings 54 and are threaded into openings 61 in the legs 30. The heads of the screws 60 are adapted to bear outwardly against the shoulders 56 so that the screws form effective connections between the legs 30 and the adjacent bushings 54. Wrench sockets 62 are provided in the outer ends of the screws 60 to facilitate the threading of the screws. The inner cutters 52 and 53 rotatably supported as just described rotate about downwardly and outwardly inclined axes to act on or form a central conical mound of earth formation which effectively centers the bit. The cutters 53 being larger in diameter than the cutters 52 form a shoulder or step in this conical surface of the formation and project downwardly to operate in advance of the lower ends of the body legs 30 and the bushing flanges 58. The ports 21 of the nozzle 19 are located and formed to direct streams of circulation fluid downwardly against the cutters 65 13, 52 and 53.

70 In assembling the bit the screws 48 are arranged in the bushings 43 and the screws 60 are arranged in the bushings 54. The cutters 13 with their bearings 45 are then assembled on the bushings 43 and the cutters 52 and 53 with

their bearings are assembled on the bushings 54. The bushings 43 and 54 are then threaded on their respective pins 37 and 39. The screws 48 and 60 are retracted or arranged so that they do not project from the ends of the bushings 43 and 54 to permit the carrier to be inserted between the legs of the body 11. Fig. 5 of the drawings illustrates the assembly of the carrier 12 and its cutters being entered in the bit body. Due to the difficulty that may be encountered in insuring the proper contact of the surfaces 47 with the surfaces 32 and the contact of the shoulders 59 with the shoulder 34 it may be preferred to cut or form the shoulders 47 and 59 during the assembling of the tool. When the assembly of the carrier 12 and its cutters has been arranged so that the shoulders 47 and 59 are in proper contact with the body shoulders 32 and 34 wrenches may be entered through the openings 50 and 61 to engage in the wrench 20 sockets 63 and 62 to thread the screws 48 and 60 into the legs. These wrenches may be such that they expand or grip the screws 48 and 60 so that the screws may be readily moved outwardly and threaded into the openings in the 25 body lugs. The threading of the screws 48 and 60 into the openings 50 and 61 finally secures the removable carrier 12 to the bit body 11. The tool is then in condition for operation.

30 In the operation of the roller bit the several 35 roller cutters 13, 52 and 53 simultaneously have rolling or cutting engagement with the formation at the bottom of the well bore as the bit is rotated. The outer cutters 13 cut the well bore to gauge and act on the outer portion of the 35 bottom wall of the well. The inner cutters 52 and 53 are rotatable about downwardly and outwardly inclined axes so that they form and engage a conical mound of the earth formation which engagement operates to center and stabilize the bit. It will be noted that the carrier 12 is not subjected to the wearing action of the rotating cutters and is not subjected to the heavy stresses during the drilling operation. The cutter supporting bushings 43 and 54 have 45 extensive surface engagement with the inner sides of the legs 29 and 30 and have shouldered engagement with the legs for the direct transmission of the drilling forces and stresses. This cooperation of the cutter supporting bushings 50 54 with the body legs relieves the carrier 12 of the transmission of the principal drilling stresses. The engagement of the shoulders on the cutter carrying bushings with the body shoulders 32 and 34 also locks the bushings against unthreading 55 from the carrier pins 37 and 39 to positively prevent loosening of the assembly.

Having described only a typical preferred form and application of my invention, I do not wish to be limited or restricted to the specific 60 details herein set forth, but wish to reserve to myself any variations or modifications that may appear to those skilled in the art or fall within the scope of the following claims.

65 Having described my invention, I claim:

1. In a roller bit, a body, a detachable carrier, a bearing part threaded on the carrier, a cutter rotatable on the bearing part, and shoulders on the body and bearing part cooperating to prevent unthreading of the bearing part 70 and to transmit forces between the body and bearing part.

2. In a roller bit, a body, a carrier removably secured to the body and having a pin, a bushing threaded on the pin, a cutter rotatable on 75

- the bushing, and cooperating shoulders on the body and bushing preventing unthreading of the bushing and transmitting drilling forces.
3. A well bit comprising a body having a leg, a carrier having a pin projecting toward the leg, a bushing threaded on the pin and having a thrust flange bearing on the inner side of the leg, and a cutter rotatable on the bushing and bearing outwardly against the flange.
- 10 4. A well bit comprising a body having a leg, a removable carrier having a pin projecting toward the leg, a downwardly facing shoulder on the inner side of the leg, a bushing threaded on the pin and having a thrust flange bearing outwardly against the leg, an upwardly facing shoulder on the flange cooperating with the first named shoulder, and a cutter rotatable on the bushing and bearing outwardly against the flange.
- 15 5. A well bit comprising a body, a leg on the body having a shoulder on its inner side, a carrier having a pin projecting toward the leg, a bushing threaded on the pin and having force transmitting cooperation with the inner side of the leg, a cutter rotatable on the bushing, and a shoulder on the bushing cooperating with the first named shoulder to transmit thrust and to prevent unthreading of the bushing.
- 20 6. A well bit comprising a body, a leg on the body having a shoulder on its inner side, a carrier having a pin projecting toward the leg, a bushing threaded on the pin and having force transmitting cooperation with the inner side of the leg, a flange on the bushing, a rotatable 25 cutter on the bushing bearing outwardly against the flange, and a shoulder on the flange cooperating with the first named shoulder for the transmission of thrusts and for preventing unthreading of the bushing.
- 25 7. In a roller bit, a body, a carrier removably secured to the body and having a pin, a bushing threaded on the pin, a cutter rotatable on the bushing, cooperating shoulders on the body and bushing transmitting thrusts and preventing unthreading of the bushing, and a screw extending outwardly from the bushing and threaded in an opening in the leg to secure the carrier to the body.
- 30 8. In a well bit, a body having a leg, a removable carrier having a pin projecting toward the leg, a bushing secured to the pin, a cutter rotatable on the bushing, and a screw extending from the bushing and threaded in an opening in the leg to secure the carrier to the leg.
- 35 9. In a well bit, a body having a leg, a removable carrier having a pin projecting toward the leg, a tubular bushing threaded on the pin, a cutter rotatable on the bushing, and a screw extending from the bushing and threaded in an opening in the leg to secure the carrier to the leg.
- 40 10. In a well bit, a body having a leg, a removable carrier having a pin projecting toward the leg, a tubular bushing threaded on the pin and having an internal shoulder, a cutter rotatable on the bushing, and a headed screw arranged in the bushing to have its head bear on said shoulder and threaded in an opening in the leg to connect the carrier with the leg.
- 45 11. In a well bit, a body having a leg, a removable carrier having a pin projecting toward the leg, a tubular bushing threaded on the pin and having an internal shoulder, a cutter rotatable on the bushing, cooperating shoulders on the leg and bushing preventing unthreading of the bushing, and a screw passed outwardly in the bushing and threaded in an opening in the leg to connect the carrier with a leg.
- 50 12. In a well bit, a carrier comprising a web, pins projecting from the opposite ends of the web, pins projecting from the opposite sides of the web, bushings threaded on the pins, and cutters rotatable on the bushings.
- 55 13. In a well bit, a carrier comprising a web, pins projecting from the opposite ends of the web, pins projecting from the opposite sides of the web, bushings threaded on the pins, flanges on the bushings, and cutters rotatable on the bushings between the flanges and the web.
- 60 14. A well bit comprising, a body having spaced legs, a carrier inserted between the legs, pins on the carrier projecting toward the legs, bushings threaded on the pins, flanges on the bushings bearing on the legs and cooperating with the legs to prevent unthreading of the bushings, cutters rotatable on the bushings, and screws connecting the bushings with the legs to attach the carrier to the body.
- 65 15. In a well bit, a body having a leg, a removable carrier having a pin projecting toward the leg, a tubular bushing threaded on the pin and having an internal shoulder, a cutter rotatable on the bushing, and a headed screw arranged in the bushing to have its head bear on said shoulder and threaded in an opening in the leg to connect the carrier with the leg, there being an accessible wrench socket in the outer end of the screw.

ALFRED C. CATLAND.
